United States Patent

Des. 239,041
Patented Mar. 2, 1976

239,041

PORTABLE SECURITY CONTAINER

Morton K. Rubinstein, 14954 Corona Del Mar,
Pacific Palisades, Calif. 90272

Filed Oct. 15, 1974, Ser. No. 514,497

Term of patent 14 years

Int. Cl. D6—04

U.S. Cl. D31—22

FIG. 1 is a schematic diagram illustrating a perspective frontal view of a portable security container in accordance with the subject invention.

FIG. 2 is a schematic diagram illustrating a rear elevational view of a portable security container in accordance with the subject invention.

FIG. 3 is a schematic diagram illustrating a bottom plan view of a portable security container in accordance with the subject invention.

I claim:

The ornamental design for a portable security container, as shown.
